CLAIM

The ornamental design for a ground scraper for closing ditches and the like, as shown.

DESCRIPTION

FIG. 1 is a front elevational view of a ground scraper for closing ditches and the like, showing my new design;

FIG. 2 is a rear elevational view thereof;

FIG. 3 is a top plan view thereof; and,

FIG. 4 is an elevational view of the right hand side of FIG. 1, the left hand side being a mirror image thereof.
